CLAIM

The ornamental design for a blood glucose meter, as shown and described.

DESCRIPTION

FIG. 1 is a top perspective view of a blood glucose meter showing our new design;

FIG. 2 is a bottom perspective view of the blood glucose meter shown in FIG. 1;

FIG. 3 is a top plan view of the blood glucose meter shown in FIG. 1;

FIG. 4 is a front elevational view of the blood glucose meter shown in FIG. 1;

FIG. 5 is a rear elevational view of the blood glucose meter shown in FIG. 1;

FIG. 6 is a left side elevational view of the blood glucose meter shown in FIG. 1;

FIG. 7 is a right side elevational view of the blood glucose meter shown in FIG. 1; and,

FIG. 8 is a bottom view of the blood glucose meter shown in FIG. 1.

The broken line showing of a test strip used with the blood glucose meter is for illustrative purposes only, and forms no part of the claimed design.
